UNITED STATES PATENT OFFICE.

CHARLES SPIRO, OF NEW YORK, N. Y.

MARGIN-STOP.

No. 902,263.

Specification of Letters Patent.

Patented Oct. 27, 1908.

Application filed August 3, 1905. Serial No. 272,605.

To all whom it may concern:

Be it known that I, CHARLES SPIRO, citizen of the United States, residing at New York, in the county of New York, State of New York, have invented certain new and useful Improvements in Margin-Stops, of which the following is a specification, reference being had therein to the accompanying drawing.

10 This invention relates to a typewriter and particularly to a construction comprising margin gage devices and other coöperating parts.

An object of the invention is to provide 15 means by which a margin stop mechanism may be capable of independent movements successive to each other whereby a secondary stop may be thrown in the path of the contact after the first is removed therefrom 20 and a longitudinal movement of the stops bodily effected to operate a line locking device.

Other and further objects and advantages 25 of the invention will be hereinafter set forth and the novel features thereof defined by the appended claims.

In the drawings, Figure 1, is a plan of the machine; Fig. 2, a side elevation thereof with parts broken away to indicate the shifting cradle; Fig. 3, a rear elevation with parts broken away; Fig. 4, a plan of the bar lock; Fig. 5, an elevation of the key projection to engage this lock; Fig. 6, a side elevation of the operating keys for the margin stops; Fig. 7, a perspective of these keys; Fig. 8, a detail perspective of the margin stop mechanism in normal position; Fig. 9, an elevation of this mechanism when shifted to operate the line lock; Fig. 10, a vertical 40 section of the margin stop in the position shown in Fig. 9; Fig. 11, a similar view with the secondary stop in engagement with the contact; Fig. 12, a like view with both of the stops therein clear of the contact; Fig. 13, a detail perspective of the means for securing the interchangeable carriage upon the cradle, and Fig. 14 is a like view of the bell ringer.

Like letters of reference refer to like parts 50 in the several figures of the drawings.

The letter A designates the frame of the machine which is provided with the usual space key A' and type levers A² at the key board thereof. The interchangeable carriage A³ may be of any desired construction and is provided with the platen A⁴ disposed

adjacent to the type bar locking device B. At opposite sides of this device the usual ribbon mechanism A⁵ is disposed and surrounding these parts the type bar segment 60 A⁶ carrying the various type bars B'. These bars are each provided with the usual type B² at their outer ends, and when used with the shiftable cradle a plurality of such type are carried by each bar. The bar has depending from the type face thereof a lug R³ having a beveled or chisel point B⁴ adapted to enter one of the series of vertical slots B⁵ provided upon the concaved face B⁶ of the bar locking plate. The provision of these 70 vertical slots permits the accurate formation of the plate and its disposition closer to the printing point so that a greater number of the slots may be used than can be provided with the ordinary construction of pins. In 75 providing a larger number of these slots they may be disposed in such alinement with the pivots of the bars as to prevent the side or torsional strain on the bar which commonly occurred when a single bar locking 80 point was provided and the bar was bent or deflected so as to enter this point.

The interchangeable carriage A³ is removably secured in position upon the cradle C in any desired manner, for instance, one 85 of the end frames A⁷ of the carriage base having the back bar A¹⁰ may be provided with a slot or recess A⁸ in its outer face which is adapted to engage the segmental head C' of the screw C² which is mounted 90 upon the cradle C of the machine. It will be seen that when the head C' is disposed within the slot, as shown in Fig. 13, the carriage base will be firmly retained to the cradle. When the screw is turned so as to 95 bring its flat face C³ opposite the slot of the carriage base, the carriage may be readily removed from the cradle. This cradle is pivotally mounted to the frame of the machine, as shown at C⁴, and may be operated 100 in any desired manner, for instance, by means of the key lever C⁵ attached to the cradle and the restoring spring C⁶ extending from the cradle to a fixed point upon the frame. This use of an interchangeable carriage upon a shiftable cradle adapted to coöperate with type bars carrying a plurality of type provides means by which any desired length of carriage and platen may be used in connection with the machine for different 111 classes of work, for instance, as is necessary in tabulating upon large sheets of paper.

- This carriage is provided at its rear beneath the paper guide or holder D with a rack or toothed bar D' extending longitudinally thereof and adapted to coöperate with a contact block D² pivotally mounted upon the carriage at D³ and having a toothed lower end D⁴ to engage the rack D' in contact with which it is held under normal conditions by means of the spring D⁵ interposed between the paper guide and the handle or finger at the upper end of the block D². This paper guide is provided upon its outer face with a scale D⁷ of the usual character by which the contact blocks may be adjusted and the paper guided into the machine. The finger portions of the blocks coöperate with said scale to indicate the position of the blocks relative to the rack bar.
- The carriage is mounted upon the frame of the machine in any desired manner, for instance, by means of the roller bearings A⁹ disposed between the same and a back bar A¹⁰ carried by the frame. This back bar also supports the margin stop mechanism E. The stop mechanism E is provided with a primary stop E' and a secondary stop E² disposed when at rest in a lower horizontal plane from the primary stop. These stops are pivotally mounted to swing away from the contact blocks D² by means of the ears E³ at opposite ends of the stop plate which are mounted upon a bearing rod E⁴ carried by the ears E⁵ at opposite ends of the plate E. This plate is also provided with a horizontally disposed contact face E⁶ for the primary stop E' and with a similar face E⁷ for the secondary stop E², while an abutment wall E⁸ is disposed at one end of the face E⁶ and a similar wall E⁹ at the opposite end of the face E⁷ both of these walls being out of alinement with the block D². These faces provide a sliding contact surface for the stops in their longitudinal movement with the carriage after the primary engagement of the contact block therewith and the stops may be restored to their normal position after being released from the carriage by means of the coil spring E¹⁰ surrounding the rod E⁴ and disposed between the ears E³ and E⁵ at one end of the mechanism. Depending from the stop plate is a finger F having an extension F' therefrom disposed at an angle to the vertical plane of the finger, as shown in Fig. 10. This extension upon its inclined wall face engages the locking hook F² adapted to engage the universal bail F³ for locking all of the key levers at the end of the line. The locking hook F² is pivotally mounted at F⁴ and is normally held with its hooked end F⁵ removed from the socket F⁶ in the universal bail by means of a tension spring F⁷ suitably mounted upon a relatively fixed part of the frame, while the upper angularly disposed end of

the hook is provided with a curved contact face F⁸ with which the extension F' engages when the margin stops are thrown upward, thus forcing the line lock hook into contact with the universal bail.

The abutment wall E⁸ is inclined upon its face next the secondary stop E² so that in the longitudinal movement of the stops the secondary stop rides upward thereon thus automatically moving the primary stop E' out of the path of the contact block or from the position shown in Fig. 10 to that of Fig. 11, and this occurs during the line locking action of the parts.

For the purpose of operating a bell ringer mechanism G in the step by step travel of the carriage the contact block is provided with a depending pin G' adapted to engage a V-shaped striker G² pivotally mounted at G³ upon the back bar A¹⁰ of the machine. This striker mechanism is provided with a depending arm G⁴ carrying a restoring spring G⁵ having its free end extended through a loop G⁶. The arm G⁴ is provided with a finger G⁷ adapted in its oscillation to strike the projection G⁸ carried by the pivoted lever G⁹ held under spring tension and adapted to engage the bell G¹⁰ in the operation of the machine. This bell ringer may be of any desired construction, that herein shown in Fig. 14 being a convenient and desirable form for the purpose.

For the purpose of oscillating the stop mechanism for different degrees of travel in order to throw either of the stops into the path of the contact block a key lever H is provided and extends to the key board of the machine where it is provided with the usual key H' which in its operation constitutes a margin lever and throws the stops entirely clear of the contact block. This lever H is pivotally mounted at the rear of the frame, as shown at H², and is connected to a rock lever H³ pivoted at H⁴ by means of a link H⁵ pivotally connected at H⁶ to said rock lever. The opposite end H⁷ of the rock lever is provided with a suitable beveled or inclined contact face H⁸ adapted in its travel to engage the member F and force the same inward, thus raising the stops and throwing the line lock into engagement with the universal bail. When it is desired to raise the stops for only a portion of their travel so that the primary stop may be clear of the contact block and the secondary stop interposed in its path this margin lever is only depressed for a portion of its travel, which is accomplished by means of a paragraph key I pivotally mounted at I' upon the margin lever and provided with a yoke I² extending over said lever and having a socket I³ at its lower portion with which the margin lever engages at the extreme of its downward movement. This paragraph key is disposed above a portion

of the frame or other fixed point, as shown in Fig. 1, and in its depression engages the frame so as to carry the margin lever downward for a portion of its travel and thus 5 limit the extent of travel of the rock shaft into contact with the stop mechanism, while the pivotal arrangement of the paragraph key or lever upon the margin lever permits a continued movement of the latter when it is desired to disengage the secondary stop from the abutment block.

In the operation of the invention the means for mounting the interchangeable carriage provided with the rack and contact 15 blocks disposed thereon permits the removal and changing of the carriage independent of the remainder of the machine and without in anywise affecting the same as either a long or short carriage may be used as found most 20 convenient or desirable for the class of work to be performed. These contact blocks are disposed at opposite sides of the stop mechanism so as to allow both to coöperate therewith and determine the opposite margins 25 upon the bar. In the travel of the carriage from right to left by the ordinary step by step feed the contact block at the right of the stop mechanism first engages the bell ringer sounding the usual warning, before 30 reaching the end of the line and then by contact with the primary stop shifts the stop plate longitudinally upon the rod and its extension throws the line lock into engagement. If it now be desired to add 35 additional letters or words to the line already written space for this purpose may be provided by depressing the paragraph key which oscillates the stop mechanism sufficiently to raise the primary stop out of the 40 path of the block and interpose the secondary stop in its path, allowing an additional number of spaces in this manner. If for any reason it be desired to entirely remove the stops the margin lever will be pressed 45 downward so that the writing may be extended into the margin at that side of the paper. In the return of the carriage to its 50 initial position for beginning another line the block at the left thereof passes over the secondary stop and engages the primary stop which establishes the uniform margin 55 on the paper, but under some conditions such as paragraphing it is desired to leave a greater space at the margin and the paragraph key is then depressed which raises the secondary stop into the path of the contact block. It will be seen that the engagement 60 of the margin lever and paragraph key provides means for oscillating the stop mechanism for different lengths of travel and this mechanism coöperates with each of the contact blocks to control the margins at both sides of the paper. The stop mechanism normally lies with the primary stop in the 65 path of the contact block and is adapted for

a longitudinal movement, a partial elevation, and a complete elevation.

Having described my invention and set forth its merits what I claim and desire to secure by Letters Patent is:—

1. In a typewriter, a margin gage mechanism comprising a plurality of transversely movable stops having contact faces disposed in different parallel planes, a support for said stops having abutments disposed at one 70 end of the faces of said stops, a carriage carrying means to engage said stops, and means at the keyboard of the typewriter connected to move said stops for different lengths of transverse travel whereby they 75 may be successively engaged.

2. In a typewriter a margin gage mechanism comprising an oscillating stop having straight contact faces disposed in different parallel planes, a carriage provided with 80 means to engage said stop, abutments for said stop, and a key lever connected to oscillate said stops for different lengths of travel.

3. In a typewriter, a margin gage comprising transversely and longitudinally movable sliding stops upon a fixed part, a carriage provided with means to engage said stops, a keyboard locking device disposed in the path of the sliding travel of said stops 90 to be actuated thereby, and a keyboard connection adapted to transversely actuate said stops out of the path of the carriage means.

4. In a typewriter, a margin gage mechanism comprising a plurality of transversely 100 movable stops disposed in different planes, a carriage provided with means to engage said stops, a key lever to actuate said stops, and a key pivotally mounted on said lever and having an extension to engage a fixed 105 part to limit its travel.

5. In a typewriter, a margin gage mechanism comprising a plurality of movable stops disposed in different planes, a carriage provided with means to engage said stops, 110 a key lever adapted to actuate said stops, a key pivotally mounted upon said lever to engage the upper face thereof, and a depending yoke from said key extended beneath said lever into its path of travel.

6. In a typewriter, a margin gage comprising an oscillating and longitudinally sliding plate having stop portions disposed in different horizontal planes, a depending arm for operating said plate, a fixed plate 120 upon which the oscillating plate is mounted, and abutments on the fixed plate to engage said stops.

7. In a typewriter, a margin gage comprising an oscillating plate having stop portions disposed in different horizontal planes, a depending arm by which the plate may be oscillated, a pivoting rod upon which said plate is mounted for reciprocatory motion, 125 abutting walls disposed in the path of travel 130

of said stops, and a tension spring surrounding said rod for retaining the plate normally at one end thereof.

8. In a typewriter, a margin gage comprising an oscillating plate having stop portions disposed in different horizontal planes, a depending arm by which the plate may be oscillated, a pivoting rod upon which said plate is mounted for reciprocatory motion, a tension spring surrounding said rod for retaining the plate normally at one end thereof, and means for locking a universal bail disposed in the path of said arm in its reciprocatory movement.

15 9. In a typewriter, a margin gage comprising an oscillating plate having stop portions disposed in different horizontal planes, a depending arm by which the plate may be oscillated, a pivoting rod upon which said plate is mounted for reciprocatory motion, a tension spring surrounding said rod for retaining the plate normally at one end thereof, and a pivoted hook adapted to engage a universal bail and having a crank arm disposed in the path of the arm from the stop plate.

10. In a typewriter, a margin gage comprising an oscillating plate having stop portions disposed in different horizontal planes, a depending arm by which the plate may be oscillated, a pivoting rod upon which said plate is mounted for reciprocatory motion, a tension spring surrounding said rod for retaining the plate normally at one end thereof, a pivoted hook adapted to engage a universal bail and having a crank arm disposed in the path of the arm from the stop plate, a rock lever having its free end disposed parallel to the arm from said stop plate, and a key lever for operating the opposite end of said rock lever.

11. In a typewriter, a margin gage device comprising a supporting plate having horizontal portions disposed in different planes and ears at its opposite ends, a pivoting rod extending between said ears, a stop plate having ears at its opposite ends pivoted upon said rod, stops carried by the upper portion of said plate and disposed upon said horizontal portions, and a depending operating arm for said plate deflected from the vertical plane thereof.

12. In a typewriter, a margin gage device comprising a supporting plate having horizontal portions disposed in different planes and ears at its opposite ends, a pivoting rod extending between said ears, a stop plate having ears at its opposite ends pivoted upon said rod, stops carried by the upper portion of said plate and disposed upon said horizontal portions, a depending operating arm for said plate deflected from the vertical plane thereof, a coil spring disposed upon said rod between the ears of the stop plate and the supporting plate, and a rock

lever having an operating free end disposed adjacent to the arm from the stop plate.

13. In a typewriter, a margin gage comprising a supporting plate having horizontal portions disposed in different planes and ears at its opposite ends, a pivoting rod extending between said ears, a stop plate having ears at its opposite ends pivoted upon said rod, stops carried by the upper portion of said plate and disposed upon said horizontal portions, a depending operating arm for said plate deflected from the vertical plane thereof, a coil spring disposed upon said rod between the ears of the stop plate and the supporting plate, a rock lever having an operating free end disposed adjacent to the arm from the stop plate, a pivoted hook adapted to engage the universal bail, a crank arm at the upper end of said hook disposed in the path of the arm from the stop plate, and a spring carried by said hook to normally retain the same out of engagement with the bail.

14. In a typewriter, a carriage provided with a paper table, a supporting bar extending longitudinally at the rear thereof and a rack disposed parallel to said bar beneath said table, a pivoted contact block slidably mounted upon said bar, a toothed inner face upon said block opposite said rack, and a handle upon the block at the rear of the upper edge of said table.

15. In a typewriter, a carriage provided with a supporting bar extending longitudinally thereof, a rack parallel to said bar, a pivoted contact block slidably mounted upon said bar, a toothed inner face upon said block at one side of the bar opposite said rack, an angular disposed handle plate at the upper portion of said block, and a tension spring bearing upon the handle plate to hold the toothed face in engagement with the rack.

16. In a typewriter, a carriage, contact blocks disposed at the opposite ends thereof, stop mechanism upon a relatively fixed part intermediate of said contact blocks and provided with a margin stop normally in the path of said blocks and a supplemental stop out of said path, and a key lever for moving said margin stop out of said path and the supplemental stop into the path of said blocks.

17. In a typewriter, a carriage, contact blocks disposed at the opposite ends thereof, a stop mechanism having a plurality of stops movable transversely and longitudinally of the carriage and disposed upon a fixed part intermediate of said contact blocks, a key lever for moving either stop of said mechanism out of the path of said blocks, and means actuated by the longitudinal movement of the stop mechanism to lock the keyboard of a typewriter.

18. In a typewriter, a carriage, contact blocks disposed at the opposite ends thereof,

2 a stop mechanism movable transversely and longitudinally of the carriage and disposed upon a relatively fixed part intermediate of said contact blocks, a key lever for moving 5 said stop mechanism transversely out of the path of said blocks, means actuated by the longitudinal movement of said mechanism to engage the universal bail and lock the keyboard of a typewriter, a depending projection from one of said blocks, and a bell 10 ringing mechanism disposed in the path of said projection.

19. In a typewriter, a carriage provided with a contact block, a transversely movable 15 stop mechanism having a support therefor and a plurality of contact faces for said block, varying in elevation from said support, and means for successively moving said faces out of the path of the block.

20. A margin gage mechanism comprising 20 a stop plate having pivoting ears thereon, separate stops bent at an angle to said plate and disposed in different horizontal planes, a depending operating arm deflected from 25 the plane of the plate, and a supporting member provided with abutments for said stops and a pivot for said plate.

21. A margin gage mechanism comprising 30 a stop plate having pivoting ears thereon, separate stops bent at an angle to the plate and disposed in different horizontal planes, a depending arm deflected from the plane 35 of the plate, and a supporting plate provided with a pivot for said stop plate and having horizontal bearing faces in different planes with an abutment wall at the upper end of each face.

22. In a typewriter, a margin gage mechanism comprising a transversely and longitudinally 40 movable sliding stop upon a fixed part, a carriage provided with means to engage said stop, an abutment for said stop having an inclined wall disposed to contact with the under face of the stop, and tension 45 means for moving the stop longitudinally from said wall.

23. In a typewriter, the combination with 50 a support, of a margin gage comprising a stop transversely and longitudinally movable thereon, a carriage provided with means to move said stop longitudinally, and a movable keyboard locking device disposed in the path of the stop for movement in unison therewith during the longitudinal 55 travel thereof.

24. In a typewriter, the combination with 60 a margin gage comprising a transversely and longitudinally movable stop having a line lock member, of a carriage provided with means to move said stop longitudinally, means to transversely actuate said stop, and a keyboard locking device having a face in the path of said member and in contact therewith during its longitudinal 65 travel for the locking action.

25. In a typewriter, a carriage provided with a contact block, a transversely and longitudinally movable stop mechanism having a support therefor and a plurality of contact faces for said blocks varying in elevation from said support, a movable keyboard locking device having means to engage the universal bail and disposed in the path of longitudinal travel of said stop for movement in unison therewith during the 70 locking action, and means for actuating said stop transversely.

26. In a typewriter, a carriage provided with a paper table, a supporting bar extending longitudinally at the rear thereof and a rack disposed parallel to said bar beneath said table, a pivoted contact block slidably mounted upon said bar, a toothed face upon said block opposite said rack, and a handle upon the block at the rear of the 80 upper edge of said table.

27. In a typewriter, a carriage provided with a supporting bar extending longitudinally thereof, a rack parallel to said bar, a pivoted contact block slidably mounted upon said bar, a toothed face upon said block at one side of the bar opposite said rack, an angularly disposed handle plate at the upper portion of said block, and a tension spring bearing upon the handle plate 90 to hold the toothed face in engagement with the rack.

28. In a typewriting machine, the combination with the carriage, of a paper table mounted thereon, a scale carried adjacent the rear edge of said paper table, a rack bar mounted upon said carriage behind the paper table, an oscillating and endwise movable margin stop block supported adjacent said rack bar and having teeth for engaging the latter, whereby said stop block may be locked in any desired position thereon, a spring interposed between a portion of said margin stop block and said paper table adapted to maintain the teeth of the former in engagement with said rack, and means carried by said stop block adapted when the same is swung from said rack bar to coöperate with said scale, to indicate the position of said stop block with respect to said rack 100 105 110 115 bar.

29. In a typewriting machine, the combination with the platen carriage, of a paper table carried thereby, margin stop blocks mounted behind said paper table and adapted to be locked in different positions longitudinally of said carriage, a scale carried by said paper table, and means carried by said margin stop blocks which coöperate with said scale to indicate the position of said stop blocks upon said carriage.

30. In a typewriting machine, the combination with the carriage, of a paper table mounted thereon, margin stop blocks adjustably mounted upon said carriage behind said 120 125 130

paper table, and a scale carried by said paper table and coöperating with means carried by said margin stop blocks to indicate the position of the latter upon said carriage.

5 31. In a typewriting machine, the combination with the platen carriage, of a paper table carried thereby, a rack bar mounted adjacent said paper table behind said carriage and an oscillatory and endwise movable stop block supported upon the platen carriage behind the paper table and having teeth for engagement with said rack, spring means for holding the teeth of said stop block in engagement with the rack, a scale 10 carried by said paper table and arranged adjacent the rear edge thereof and an indicating finger carried by said margin stop block adapted, when the same is swung from engagement with said rack bar, to move into 15 adjacency with said scale and coöperate therewith to indicate the position of said stop block with respect to said rack bar.

32. In a typewriting machine, the combination with the carriage, of a paper table 25 carried thereby, margin stop blocks supported upon said platen carriage behind said paper table and longitudinally movable in their supports, fingers carried by said margin stop blocks, and a scale carried by the 30 paper table with which said fingers coöperate to indicate the position of said stop blocks upon said carriage.

33. In a typewriting machine, the combination with the platen carriage, of a paper 35 table carried thereby, a rack bar mounted upon said platen carriage behind the paper table, a margin stop block having teeth engaging those of said rack bar whereby said stop block may be locked in any desired position with respect thereto, a support for 40 said margin stop block in which the same may swing from said bar or move longitudinally, a spring carried by said margin stop block and engaging said paper table 45 to hold the teeth of the former in engagement with said rack, an indicating member carried by said margin stop block, and a scale mounted upon said paper table adjacent the rear edge thereof with which said 50 indicating member coöperates when the margin stop block is swung upwardly to disengage the teeth thereof from those of said rack to indicate the position of said stop block upon said rack.

55 34. In a typewriting machine, the combination with a platen carriage, of a paper table carried thereby, margin stop devices

mounted upon said carriage behind said paper table, a scale carried by said paper table and longitudinally adjustable thereon, and means carried by said margin stop devices which coöperate with said scale to indicate the position of the former with respect to said platen carriage.

35. In a typewriting machine, the combination with the carriage, of a paper table 60 mounted upon said carriage, a scale bar carried by said paper table, a rack mounted upon the carriage behind the paper table, and a margin stop block slidably mounted relative to said rack and having means coöperating with said scale to indicate its position upon said rack.

36. In a typewriting machine, the combination with the carriage, of a paper table 65 mounted thereon, a scale carried by the paper table, a rack located upon said carriage behind the paper table, a stop block slidably mounted relative to said rack and adapted to be located at any desired position thereon, and a pointer carried by said stop block and coöperating with said scale to indicate the position of said stop block upon said rack.

37. In a typewriting machine, the combination with the carriage, of a paper table 75 mounted thereon, a scale bar positioned upon said paper table at the rear portion thereof, a rack bar mounted upon said carriage behind the paper table, a plurality of stop blocks slidably mounted relative to said rack bar and adapted to be locked thereto, and a pointer extending upwardly from each of said stop blocks to a position adjacent said scale bar and adapted to coöperate therewith 80 to indicate the positions of said stop block upon said rack bar.

38. In a typewriting machine, the combination with the carriage, of a paper table 85 mounted thereon, a rack bar mounted behind the paper table, a scale carried by said paper table adjacent the rear edge thereof, margin stop blocks slidably mounted relative to said rack bar, and means carried by said blocks and arranged adjacent said scale and coöperating therewith to indicate the positions 90 of said stop blocks upon said rack bar.

In testimony whereof, I affix my signature in presence of two witnesses.

CHARLES SPIRO.
